UNITED STATES PATENT OFFICE.

HENRY GARDENIER, OF PATERSON, NEW JERSEY.

WATER-SUPPLY VALVE.

No. 924,052.

Specification of Letters Patent.

Patented June 8, 1909.

Application filed April 6, 1907. Serial No. 368,861.

To all whom it may concern:

Be it known that I, HENRY GARDENIER, a citizen of the United States, residing at Paterson, in the county of Passaic and State of New Jersey, have invented certain new and useful Improvements in Water-Supply Valves, of which the following is a specification, reference being had therein to the accompanying drawing.

10 The object of my invention is to render more simple and expeditious the replacing of an elastic or flexible diaphragm or packing in water-supply valves; to provide an economical form of packing that may be inserted and removed with facility; to simplify the construction of water supply valves and their accessories; to provide a valve in and from which the packing may be placed and removed without separating and unscrewing 20 the parts of the valve structure or casing; and to obviate the many difficulties experienced by plumbers in replacing old and worn out packing by new in all the types of water-supply valves now in vogue.

25 In the valves now in use the packing is not easily accessible and can only be reached and removed by unscrewing the parts that enclose it, which is often a difficult job owing to the corrosion or rust resulting from the action of the water or chemical ingredients contained therein.

The invention consists of a valve and valve casing of simple and novel construction into which the packing is inserted from the outer side without dismemberment of the valve or casing.

The invention is illustrated in the accompanying drawings, in which—

Figure 1 is a vertical sectional view of a ball-cock valve with my improvements, the elastic or flexible diaphragm or packing being inserted and secured from the outside of the valve-casing; Fig. 2 is a top plan view thereof; Fig. 3 is a vertical view part sectional through the outlet chamber, on the line —X—X— in Figs. 1 and 2; and Fig. 4 is a cross-sectional view on the line —y—y—in Fig. 3.

From an examination of the drawings it is 50 obvious that the diaphragm packing may be

inserted and withdrawn without the slightest difficulty, and the utility and economy of the construction is apparent.

The valve-casing —1— may be constructed of one piece, having the port —2—, valve-seat —3— and the opening H.

The plunger —4— is operated by the lever —7— to which the ordinary ball is secured.

My so-called packing, —5— is similar to a tongue the inner end of which is loose and free to vibrate and is inserted from the outside of the valve-casing, through an aperture formed for the purpose, as shown in the drawing, and is securely held in place, at its outer end, by the screw —6— which permits the inner end to move or vibrate, and to be raised by the inflow of water when the plunger —4— is elevated, and to be forced down, closing the port —2—, when the plunger is lowered.

In the drawings —8— is the outlet or discharge from chamber —11— and —14— the refill tube, which may be connected with the outlet chamber —11— as shown in Fig. 3, or a place —9— in Fig. 2 may be tapped for it if desired. The vertical members —10— are provided with bearings for the float-lever —7—.

In most water-supply valves packing or cups are employed to prevent the water from spouting up around the plunger, and I obviate the necessity of having such packing or cups which are difficult to replace, by providing my plunger with a projecting rim —12—, shown in Figs. 1 and 3.

Dotted lines in Fig. 1 show how the free or inner end of my removable, flexible packing or diaphragm is raised to open the port —2—, and the solid lines how it closes the port.

In Fig. 4 a plan view of my packing or diaphragm is shown and the straight sides 13 of the aperture H through which it is inserted so that the packing may not shift from its proper position.

With this description of my invention, 95 what I claim, and desire to secure by Letters Patent, is—

In a ball-cock water supply valve, the combination of the casing having a valve seat, and a lateral opening in alignment 100

therewith, a plunger to coöperate with said valve seat, a flexible diaphragm between said seat and plunger, said diaphragm being adapted to be inserted and removed through said lateral opening and to be operated in one direction by the pressure of the water and in the other direction by the said plunger, means for operating said plunger,

and means to secure said diaphragm within said opening.

In testimony whereof I affix my signature in presence of two witnesses.

HENRY GARDENIER.
